UNITED STATES PATENT OFFICE.

LOUIS KOSSUTH JOHNSON AND ABBOT AUGUSTUS LOW, OF NEW YORK,
N. Y., ASSIGNEES TO THE ALDEN TYPE MACHINE COMPANY, OF SAME
PLACE.

TYPE-CONTAINING CHANNEL.

SPECIFICATION forming part of Letters Patent No. 657,874, dated September 11, 1900.

Application filed January 18, 1899. Serial No. 702,517. (No model.)

To all whom it may concern:

Be it known that we, LOUIS KOSSUTH JOHNSON and ABBOT AUGUSTUS LOW, citizens of the United States, residing in New York, borough of Brooklyn, in the county of Kings and State of New York, have invented certain new and useful Improvements in Type-Containing Channels, of which the following is a specification sufficient to enable others skilled in the art to which the invention appertains to make and use the same.

Our improvements relate to type-containing channels generally, but more particularly to those designed for use in type apparatus in which the types are arranged upon their flat sides, as in the numerous type-setter cases heretofore patented by us, in which the types are forwarded successively from the lower end of a channel by a reciprocating pusher into position to be conveniently removed by the hand of the compositor. In the present instance our improvements are designed to afford a type-containing channel of comparatively cheap and simple structure, the parts of which may be readily assembled or separated and are interchangeable. By our invention the channel is readily adaptable to different fonts of type and affords convenient access to the types when in the channel.

The invention consists in the special construction, arrangement, and combination of parts hereinafter set forth.

In the accompanying drawings, Figure 1 represents a side elevation of our improved type-containing channel; Fig. 2, a view of the interior of the channel, the right-hand side plate being removed; Fig. 3, a similar view with the left-hand side plate removed; Fig. 4, a front edge view; Fig. 5, a rear edge view; Fig. 6, a sectional elevation showing types in the channel; Fig. 7, a sectional elevation upon plane of line 7 7, Fig. 1. Fig. 8 is a top view; Fig. 9, a similar view with the retaining-strips omitted; Fig. 10, a transverse section upon plane of line 10 10, Fig. 1; Fig. 11, a transverse section upon plane of line 11, Fig. 1; Fig. 12, an isometrical perspective of a portion of one of the retaining-strips; Figs. 13 and 14, isometrical views of

opposite sides of one of the spacing-blocks; Fig. 15, an isometrical view of the lower spacing-block, showing the pusher-way. Fig. 16 is a top view of the channel, showing the relation of the retaining-strips to the type. 55 Figs. 12, 13, 14, 15, and 16 are shown upon an enlarged scale.

Our improved type-containing channel consists, essentially, of two plates A and A', united by spacing-blocks B. These spacing-blocks B are of a thickness equal to the width of the type to be accommodated, so that by having a series of blocks B corresponding in thickness to different fonts of types the side walls may be adapted to the requirements of 65 a corresponding series of fonts. The side walls are attached to the blocks B by screws s, the heads of which are preferably countersunk in the side walls, as indicated in the drawings. 70

In order to guide and retain the types within the channel, we provide strips c c, preferably of flat sheet metal, which extend longitudinally within the channel and at either side thereof. These strips act as guiding- 75 shoulders to the types, the one abutting against the heels of the types, the other against the shoulders t upon the face of the types, as clearly illustrated in Fig. 16. The strips c c are clamped in position by and between the inner surface of the side walls and the adjoining surfaces of the spacing-blocks B, the latter being formed with offsets or recesses b b for the reception of the strips. In lieu of strips of flat sheet metal strips of 85 wire may be substituted, to be stretched between the spacing-blocks for the purpose of preventing the movement of the types in the line of their longitudinal axes. 80

The plates A A' are formed with longitudinal openings L L, those in the opposed walls preferably coinciding with each other, so as to afford convenient access for the finger and thumb of the handler in correcting the alignment of the types, if necessary, or otherwise 90 manipulating them or the slug or follower. The openings L L also render the types visible, so that the condition of the channel and its column of type can be readily ascertained. 95

Our channels may be taken apart for con- 100

venient storage when not required for use or for the sake of economy in transportation and may be again quickly assembled by unskilled labor. In fact, the parts being ⁵ interchangeable and spacing-blocks of different thicknesses being provided, our improvements afford and render possible what may be designated as a "universal knockdown channel" or series thereof adapted to all the ¹⁰ different requirements of practical use in connection with fonts of types of different sizes.

What we claim as our invention, and desire to secure by Letters Patent, is—

The combination of the side walls A, A',

formed with the longitudinal openings L, L, ¹⁵ the spacing-blocks B, B, formed with the offset b, b, the longitudinal shoulder-strips c, c, fitting in the offsets b, b, in the blocks B, B, and the screws s, s, for binding the parts together to form a rigid type-containing channel, substantially in the manner shown and described. ²⁰

LOUIS KOSSUTH JOHNSON.
ABBOT AUGUSTUS LOW.
